(57) **CLAIM**

The ornamental design for a sky projection lamp, as shown and described.

DESCRIPTION

FIG. 1 is a front and top perspective view of a sky projection lamp design showing my new design.

FIG. 2 is a rear and bottom perspective view of a sky projection lamp.

FIG. 3 is a front view of a sky projection lamp.

FIG. 4 is a rear view of a sky projection lamp.

FIG. 5 is a left side view of a sky projection lamp.

FIG. 6 is a right side view of a sky projection lamp.

FIG. 7 is a top view of a sky projection lamp.

FIG. 8 is a bottom view of a sky projection lamp.

FIG. 9 is an enlarged view of a sky projection lamp, as shown in FIG. 3; and,

FIG. 10 is an enlarged view of a sky projection lamp, as shown in FIG. 4.

The broken-line circle, which illustrates the boundary of the enlarged view shown in FIGS. 3, 9 and 10, along with the related straight broken line in FIG. 3, together represent a detail callout, which form no part of the claimed design.
